FIG. 3.

UNITED STATES PATENT OFFICE

WILBUR H. ARMACOST, OF NEW YORK, N. Y., ASSIGNOR TO THE SUPERHEATER COMPANY, OF NEW YORK, N. Y.

SUPERHEATER BOILER

Application filed March 28, 1929. Serial No. 350,566.

My invention relates to superheater boilers and has particular reference to large power boilers designed to operate at relatively high pressures.

In boilers of this general character, the size of the individual elements together with the high saturated steam temperatures encountered result in expansion and contraction of parts of the boiler with respect to each other of such magnitude that the satisfactory mounting of such elements has proved to be a very difficult problem.

One of the principal objects of the present invention is the provision of a novel boiler construction particularly with reference to the arrangement of boiler drums and superheater headers which will provide a degree of flexibility hitherto unobtained and sufficient to take care of the extreme expansions and contractions encountered in high pressure boilers. Numerous other objects and advantages incident to my invention will be more specifically pointed out in the ensuing description of the several embodiments thereof illustrated in the accompanying drawings forming a part hereof, in which Fig. 1 is a fragmentary vertical section showing the upper portion of a superheater boiler embodying the invention; Fig. 2 is a fragmentary section taken along the line 2-2 of Fig. 1; Fig. 3 is a vertical section illustrating another form of the invention; and Fig. 4 is a fragmentary section of a still further modified form of the invention.

Referring now to Fig. 1, the boiler chosen for illustrative purposes is of the double semi-vertical type comprising twin steam generating units A and B mounted in a common setting. One of the units comprises the steam and water drums 1 and 2 connected by the banks of steam generating tubes 3, 4 and 5 to the usual mud drums (not shown). Water circulators 6 and steam circulators 7 connect drums 1 and 2 in the usual manner. The second steam generating unit is similar in form to the one just described and comprises steam and water drums 8 and 9, banks of generating tubes 10, 11 and 12, water circulators 13 and steam circulators 14.

The generating units are fired from a com-

mon furnace 15 and in the form shown the gases from the furnace are directed in three passes over each of the generating units by means of baffle 16 as indicated by the arrows on the drawings, to the usual separate outlet flues or breechings (not shown). The specific form and baffling arrangement of the boiler is not germane to the present invention, and a more detailed description thereof is therefore not deemed necessary herein.

The generating units A and B are provided respectively with elevated steam drums 17 and 18, drum 17 being connected to drum 1 by a plurality of rows of tubes 19 which, as will be observed from Fig. 2, are uniformly distributed over substantially the entire length of the drums. The number of rows of tubes employed will vary according to the capacity and rating for which the boiler is designed, but it is preferable to provide a sufficient number of tubes so that the steam velocity through tubes 19 does not exceed a velocity of 100 feet per second. The reason for this will appear later. A similar group of tubes 20 serves to connect the drums 9 and 18.

Drums 17 and 18 may be provided with baffles 21 and 22 and drainage tubes 23 and 24, the latter preferably being connected respectively to drums 1 and 9.

The drums 17 and 18 are connected respectively by rows of tubes 25 and 26 to a header 27 which will hereinafter be referred to as an intermediate header. Tubes 25 and 26 are arranged along substantially the full length of drums 17 and 18 and header 27 in the manner shown more clearly in Fig. 2. It is preferred that the total cross section of tubes in group 19 and the tubes in group 20 be greater than the total cross section of the tubes in group 25 and the tubes in group 26, and for this purpose the tubes in group 19 are made more numerous, as shown, than those in group 25, and the tubes in group 20 more numerous than those of group 26, the individual tubes being assumed to have the same cross section in each of the separate groups.

As shown, the superheater comprises an inlet header 28 and an outlet header 29 con-

nected by a plurality of tubular superheater elements 30 arranged in two groups one of which extends into the intertube space of the tube bank 5 and the other of which is similarly positioned in tube bank 12. Elements 30 are preferably so formed that, when in place, the portions passing through the roof of the boiler are vertical and as, in all the forms of the invention illustrated, the lateral 5 thrusts on the superheater headers 28 and 29 are substantially balanced, what residual motion there may be between the superheater headers and the steam and water drums of the boiler units will be almost exactly 10 vertical so that the vertical position of the elements at the points where they penetrate the boiler setting reduces to a minimum the stresses on the joints of the superheater and on the setting. 15 The intermediate header 27 is closed at one end and at its other end is connected by means of the pipe 31 to the corresponding end of the superheater inlet header 28. The superheater outlet header 29 discharges 20 through pipe 32 at the end opposite the inlet end of header 28.

In the type of boiler shown, the boiler proper is ordinarily suspended from above through the medium of a steel framework, 25 and in the form illustrated I have shown the boiler suspended from the transverse beams 33 by means of a number of straps or slings 34 passing around the drums 1, 2, 8 and 9. Drums 17 and 18 may be mounted as 30 shown upon saddles 35. The superheater headers 28 and 29 are carried by slings or straps 36, while the intermediate header 27 is mounted in saddles 37 on the beams 33. The saddles 37 are preferably of any known 35 form of resilient or spring type and drums 17 and 18 may also, if desired, be spring suspended although spring suspension of these drums is not essential.

It will be obvious to those skilled in the 40 art that the specific manner of supporting the several drums and headers is subject to wide variation, but it is to be noted that the steam and water drums of the boiler are fixedly supported with respect to the position of the superheater headers so that the 45 relative position of these drums with respect to the headers remains unchanged. This is important as it prevents displacement of the superheater elements 30 with respect to the boiler under the influence of expansion or 50 contraction, and therefore eliminates difficulties due to leakage at the points where the superheater elements pass through the portion of the boiler setting indicated at 38. 55 This relatively fixed position as between the boiler drums and the superheater headers is made possible by the flexibility of the connections between the steam and water drums of the generating units and the superheater headers. 60 Instead of the usual rigid piping

connection from steam nozzles on the boiler drums to the superheater inlet header, I have substituted a flexible tubular structure by means of which the steam off-take drums of the generating units are connected to an intermediate header and the only rigid connection is the relatively short pipe 31 connecting this intermediate header with the superheater inlet header. With the superheater inlet header in fixed position, expansion and contraction in the short pipe 31 is taken care of by the slight movement of the intermediate header 27, such movement being permissible because of the relatively flexible connection between this header and drums 17 and 18 provided by tubes 25 and 26.

The relatively flexible tubes 19 and 20 also absorb the expansion stresses so that drum 17 may be mounted in a relatively fixed position with respect to drum 1 and drum 18 in a relatively fixed position with respect to drum 9. In some extreme cases it may be desirable to mount drums 17 and 18 on spring saddles or their equivalent, in order to provide freely flexible units connecting drums 1 and 9 with the intermediate header 27.

A further and very important advantage which is derived from the use of my invention lies in the improved distribution of steam flow from the boiler drums to the superheater which the construction illustrated secures. Because of the large number of tubes 19 and 20 which may be employed between the steam and water drums and the steam drums, the velocity of the steam leaving the steam and water drums may be reduced to a rate below the critical velocity at which it is practically impossible to separate entrained moisture. This velocity is in the neighborhood of 100 feet per second. Furthermore, the distribution of these tubes along the entire length of the steam drum assures even flow of the steam from the drums as contrasted with the uneven flow taking place when steam is taken from the steam and water drum through one or more nozzles delivering to large steam pipes.

Drums 17 and 18 serve to separate what little moisture may be carried over from drums 1 and 9, and the distribution of steam flow from these drums is also relatively uniform along the length of the drums because of the arrangement of tubes 25 and 26. There will be a certain tendency to disturb the evenness of flow from these drums due to the pressure drop through the intermediate header 27 but steam flow through the connecting tubes 25 and 26 will be maintained at a relatively uniform rate due to the fact that the increased velocity through some of the tubes 25 and 26 which would be the result of unequal distribution would cause an increase in the resistance to flow through the tubes carrying the greatest amount of steam, and this increase in resistance in some of the tubes

would tend to establish an equilibrium of flow in which the steam distribution is substantially uniform.

The arrangement described further permits the advantageous arrangement of cross-flow through the superheater, that is, the placing of the inlet end discharge connections to the superheater at opposite ends thereof to insure the most uniform distribution of steam through the superheater elements.

It will be noted that a balancing connection between the steam and water drums of the two generating units is provided through the flexible connection formed by header 27, drums 17 and 18 and tube rows 19, 20, 25 and 26. This connection is of relatively large area so that a quick balancing of pressures between the two generating units may be secured. This is highly important in boilers of this type, particularly where the combustion gases leave through separate flues, as any change in the flue gas regulation which causes an unequal flow, even though it is only momentary, of gases over the two units causes the differential pressure within the boiler units which must be immediately equalized if a dangerous drop or rise in the water levels of the two units is to be avoided.

Heretofore it has been common practice to connect drums 2 and 8 in this type of boiler by water circulators similar to circulators 3 and 13. The circulation between drums 2 and 8 is, however, normally very sluggish, and the circulators connecting the drums are moreover exposed to very intense heat. This combination of circumstances frequently results in serious trouble with these circulators, due to overheating through lack of circulation or because of sludge accumulations which the circulation between these two drums is insufficient to carry away. With the novel arrangement of my invention, these circulators may be omitted as shown in Fig. 1, as pressure equalization between the drums is sufficiently rapid through the steam space provided to quickly equalize pressure between the two units. If an additional equalizing path is desired, tubes may be provided directly connecting the steam spaces of 2 and 8, but because of the path provided between these drums by way of drums 17 and 18 and header 27, the number of tubes directly connecting drums 2 and 8 may be greatly reduced, or, as I have shown, entirely omitted.

A still further advantage of my invention resides in the decreased cost of constructing the boiler due to the elimination of steam nozzles and steam piping. In high pressure boilers the cost of constructing drums with large nozzles secured thereto for steam off-take purposes is excessive as is also the cost of high pressure steam piping. It will be observed that if constructed in accordance with my invention, no nozzles whatever are

required and the steam piping is reduced to a minimum which, moreover, is of the least expensive form comprising short straight lengths and elbows.

Coming now to Fig. 3, the invention is shown in a slightly modified form applied to a boiler comprising twin generating units A' and B'. The unit A' comprises a single steam and water drum 1' connected by means of banks of generating tubes 3', 4' and 5' to a mud drum 39, while the similar unit B' comprises the steam and water drum 9', connected by tube banks 10', 11' and 12' to the mud drum 40. The mud drums 39 and 40 are connected through the usual water screen tubes 41 lining the furnace and combustion chamber 15'. Suitable baffling directs the combustion gases over the generating units as indicated by the arrows to the separate breechings shown. Drums 1' and 9' are connected respectively by the rows of tubes 19' and 20' to a single steam drum 42 which serves the same purpose as the drums 17 and 18 shown in Fig. 1. Drum 42 may be provided with baffles 21 and 22 and suitable water return pipes. Tubes 25 and 26 connect drum 42 with intermediate header 27' which is connected in the manner shown in Fig. 2 to the superheater inlet header 28'. The superheater arrangement is the same as shown in Fig. 2. The superheater headers are in this form also supported from the usual framework in relatively fixed relation with respect to drums 1' and 9'.

It will also be obvious that the several advantages secured by the construction shown in Figs. 1 and 2 will also be inherent in the structure shown in Fig. 3.

In Fig. 4 I have shown a further modification of the invention which is generally applicable to boilers of smaller capacity and designed to operate at relatively lower ratings. In this form the steam and water drums 1'' and 9'' are connected directly to the intermediate header 27'' by means of the rows of tubes 43 and 44 which serve to absorb all of the expansion strains. It will be observed that in this form of construction the same advantages relative to steam distribution and balancing of pressures between the generating units and other advantages previously pointed out are secured.

From the foregoing description of various embodiments of the invention it will be obvious that it is subject to many changes and variations and the forms herein shown are therefore to be considered as illustrative only, the scope of the invention being understood to embrace all that may fall within the purview of the appended claims.

I claim:

1. A superheater boiler comprising a pair of steam generating units each having a steam and water drum, a superheater having an inlet header, an intermediate header con-

5 nected to the inlet header, means located above the level of the steam and water drums and forming a steam separating space, a plurality of relatively flexible tubes connecting the steam space of each of said drums and said means, and a plurality of relatively flexible tubes connecting said means and said intermediate header, there being a greater number of tubes between said drums and said means than between said means and said intermediate header.

10 2. A superheater boiler comprising twin steam generating units of the semi-vertical type, each of said units having a steam and water drum and a steam drum, a plurality of rows of relatively small tubes connecting each of said steam and water drums with its respective steam drum, a superheater having an inlet header, an intermediate header, a plurality of rows of relatively small tubes connecting each of said steam drums with said intermediate header, and a pipe connecting the intermediate header with the superheater inlet header.

15 25 3. A superheater boiler comprising twin steam generating units of the semi-vertical type, each of said units having a steam and water drum and a steam drum, a superheater having an inlet header relatively fixed with respect to said steam and water drums, an intermediate header, a pipe forming a rigid connection between the intermediate header and the inlet header, and a plurality of relatively flexible tubes connecting the intermediate header with the steam space of each of said steam drums and a plurality of substantially flexible tubes connecting each of said steam drums with said steam and water drums.

20 40 4. A superheater boiler comprising twin steam generating units of the semi-vertical type, each of said units having a steam and water drum, a steam drum located above said steam and water drums and connected thereto, a superheater common to said units and having an inlet header relatively fixed with respect to said steam and water drums, an intermediate header of substantially the same size as said inlet header, a pipe forming a rigid connection between the intermediate and the inlet headers, and a plurality of relatively flexible tubes connecting the intermediate header with said steam drum.

25 45 5. A superheater boiler comprising a pair of steam generating units each having a steam and water drum, a superheater having inlet and outlet headers one above the other, relatively fixed with respect to said drums and having two groups of elements, one for each of said units, connected to said headers in parallel, an intermediate header of substantially the same size as said inlet header and arranged in the same vertical plane as said inlet and outlet headers, means connecting said intermediate header to said inlet

header, and a flexible connection extending the entire distance between each of said steam and water drums and said intermediate header and including tubes of small section relatively to said headers.

70 50 6. A superheater boiler comprising a pair of steam generating units each having a steam and water drum, a roof section intermediate said drums, a superheater having inlet and outlet headers arranged one immediately above the other and relatively fixed with respect to said drums and having two groups of elements, one for each of said units, connected to said headers in parallel, said elements each having vertical portions extending through said roof section, an intermediate header of substantially the same size of said inlet header, and arranged in same vertical plane as said headers, a connection between said inlet and intermediate headers, and a flexible connection extending the entire distance between said steam and water drums in said inlet header and including a plurality of conduits of small size relatively to said headers.
